UNITED STATES PATENT OFFICE.

ALBERT T. HULL, OF NEW YORK, N. Y., ASSIGNOR TO EDWARD D. FISHER,
OF SAME PLACE.

HOD-ELEVATOR.

SPECIFICATION forming part of Letters Patent No. 290,285, dated December 18, 1883.

Application filed March 17, 1883. (No model.)

To all whom it may concern:

Be it known that I, ALBERT T. HULL, a citizen of the United States, residing at New York, in the county of New York and State 5 of New York, have invented certain new and useful Improvements in Hod-Elevators; and I do hereby declare the following to be a full, clear, and exact description of the invention, such as will enable others skilled the art to 10 which it appertains to make and use the same.

The invention relates to improvements in hod-elevators, the object being to produce an effective elevator which will occupy the minimum amount of space in the building in which 15 it is used.

The invention also relates to a novel method of operating a hod-elevator, whereby the same may be placed in a chimney or small space without interfering with its successful use.

20 Referring to the accompanying drawings, Figure 1 is a side view of an elevator embodying the elements of the invention. Fig. 2 is a detached front view of same. Fig. 3 is an enlarged view of the blank for forming the 25 cross-bar. Fig. 4 is an edge view of same when finished. Fig. 5 is an enlarged view of a single link having pockets. Fig. 6 is a view of the recessed wheels for moving the chain. Figs. 7, 8, and 9 are views of the guides for 30 preventing the sagging of the chain. Fig. 10 is a view of the wheels employing the guiding-flanges.

A B denote the two sides of the endless elevator chain or belt, which passes over the pulleys C D at the top and bottom of the building in the customary manner, and is actuated by power of any suitable kind, placed either at the lower or upper end of the chain or elsewhere, as the circumstances attending its use 40 may render most desirable. The formation of the pulleys D constitute one part of my invention, and will be fully described herein-after.

The sides A B of the chain are formed of 45 double and single links pivoted together at their ends. At suitable intervals the links of the chain, either the double or single, as may be preferred, are provided with the ears E, forming pockets a, one opening upward and 50 the other downward. The pockets formed by

the ears are employed for sustaining the hod during its ascent and descent.

The hod consists of the usual bowl, b, and iron yoke d, having a handle, f.

The hod illustrated in this application is an 55 improvement on the hod described in a pending application heretofore filed by me, and numbered 84,727, said improvement consisting in curving the sides of the yoke d slightly toward the open end of the hod, whereby 60 when the carrier is placing the hod upon the chain it will be unnecessary for him to come in such close proximity thereto as will be required when the sides of the yoke are on the same vertical plane with the handle. 65

In placing the hod upon the chain, it is customary to leave it upon the shoulder of the carrier until its end is between the sides of the chain. Thus it will appear obvious that there is danger—unless the sides of the yoke 70 are curved, as specified—of the clothing or flesh of the carrier being injured by the pockets of the chain. The projections e, formed on the yoke d, are provided with the annular groove x, and have knobs on their ends, the 75 purpose of which will be understood from the description hereinafter presented. The sides A B of the chain are connected at proper intervals by cross-bars F, which are provided at about their center with notches h, if deemed 80 necessary, to facilitate the operation of the apparatus, and are provided on their ends with the flanges i. The cross-bars F may be stamped out of sheet metal with the flanges i, which flanges will then be bent at right angles to the 85 longitudinal center of the bar, and may constitute links for the chain. The bars F, with their flanged ends i, may also be made of malleable iron, if desired.

Heretofore in the construction of hod-elevator chains of the character herein described, the cross-bars have been separate from the chain, and have been secured thereto by bolts, rivets, or other means, and have been a source of annoyance, owing to the fact that the devices for securing them necessarily weakened both chain and bar—a defect which is effectively overcome by my present invention. 90 95

When the apparatus is in use in tall buildings, it has been found that the chain or belt, 100

about midway between the pulleys over which it travels, sags considerably, and jars, as a consequence, the hods secured upon its sides. When a hod on the descent side of the chain 5 is opposite to one on the ascent side, the sagging will sometimes cause the two to knock together, and there is danger of one or the other being thrown from the chain, unless the sustaining-pulleys are large enough to allow 10 a large space between the two sides of the chain.

One part of my invention consists in a novel arrangement of wheels or guides for preventing this sagging of the chain, and they are shown in Figs. 7, 8, and 9. In Figs. 7 and 8 the device consists of two wheels, L L, preferably flanged, as shown, which snugly fit between the two sides of the chain A B. Beyond these wheels L are smaller pulleys M, which, 20 when in use, are arranged to press against the outer edges of the sides of the chain and keep said sides against the large wheels L. It will be seen, therefore, that the sides A B of the chain have their movement between the 25 flanges of the wheels L, and are retained therein by the smaller wheels M.

The modified form of guide for preventing the sagging of the chain (illustrated in Fig. 9) consists in the pairs of smaller pulleys or 30 wheels N, which will be flanged or made plain, as may be preferred; but in the present instance one of the wheels is flanged, the other having a plain surface. The sides of the chain will pass between these smaller pairs of wheels in the same manner and with the same result as in the device illustrated in Fig. 7. These guides (illustrated in Figs. 7, 8, and 9) may be arranged in a separate frame and secured in the building in proper position to receive the 35 sides of the chain; or they may be attached to the joists of one of the middle floors of the building, as may be preferred. When the guides are to be attached to the joists, the flanged axle illustrated at P in Fig. 9 may be 40 used with good results. It will not be necessary in all cases to employ the guide-wheels on both the ascending and descending sides of the chain, since the weight of the full hods will materially lessen the sagging and swaying 45 of the chain on its descending side.

In the operation of the apparatus hereinbefore described, the full hods are inserted between the sides of the chain and the ears e 50 rested in the pockets a, in which position they will be elevated to the top of the building. The hods, after having been removed and emptied, are replaced on the descending side 55 of the chain sidewise—that is, instead of being inserted between the sides, as during their elevation, they are now placed with their side against the side of the chain—and the projection e inserted in the notches h, formed in the cross-bars F. When in this position, the annular groove x, formed in the projections e on 60 the side of the hods bearing against the chain, will rest in the said notches h, and prevent the

escape of the hod until it is removed at the lower part of the building. It will be observed that by means of this method of placing the hods upon the chain, small pulley-wheels may be used at the top and bottom of the building, and that the two opposite sides of the chain may be brought close together, and the hods may be elevated and returned without danger of striking each other, and 75 without occupying but a small space.

It has often been found impracticable to use hod-elevating apparatus in old buildings on account of the small extent of the hatchway, and in new buildings because it is desired 80 always to leave but a small opening in the floors as the building progresses; and in the construction of the apparatus herein described and in its method of operation I have aimed at the production of an elevator which may 85 be used in a small compass—such as a chimney, for instance—which use would leave the balance of the building unopened. The employment on the hod of projections having annular grooves x effectually prevents the lateral 90 spread of the sides of the chain, and obviates the necessity of using numerous cross-bars.

The wheels D constitute, as aforesaid, one part of my invention. They are provided on their outer side with the guiding-flanges D', which direct the chain into the grooves E', (when said grooves are used,) formed in the periphery of the main part of the wheels. The grooves E' conform in outline to the exterior contour of the links of the chain, as shown in Fig. 6, which illustrates one wheel with the chain removed. When power is applied to the wheels D, their movement is communicated to the chain by the force of the shoulders a', exerted against the ends of the double links. If preferred, the guiding safety-flanges D' may also be employed with entirely satisfactory results on wheels having teeth x' on their periphery to engage the links of the chain. (See Fig. 10.) The flanges D' effectually prevent the chain from losing its position on the wheels, and act as guides, which constantly direct the links upon the teeth or into the grooves, according to which are employed. The flanges D' add to the safety of the apparatus, and do 105 not interfere in any way with the movement and proper operation of the chain.

What I claim as my invention, and desire to secure by Letters Patent, is—

1. The method of elevating hods, which consists in causing the hod to be inserted between the sides of the chain and carried upward endwise, while on the descending side the hods are carried downward sidewise, as set forth.

2. In a hod-elevator, the sides A B of the chain or belt, having pockets, in combination with the hod provided with projections, adapted to fit into said pockets, and having enlargements on their ends, which prevent the lateral spread of the sides A B, substantially as set 125 forth.

3. The cross-bar blank for the endless chains

of hod-elevators, consisting of the bar F and flanges i, substantially of the form described, and illustrated in Fig. 3.

4. An endless chain for a hod-elevator, consisting of the independent sides A B, connected at intervals by cross-bars, and composed of open and closed links, a portion of which are provided with ears E, forming pockets a a, the ears being formed directly on the link, substantially as set forth.

5. In combination with an endless chain for a hod-elevator, the hod consisting of the bowl, the handle, and yoke d, the sides of the yoke inclining toward the open end of the hod, and provided with projections adapted to fit in the pockets on the chain, substantially as set forth.

6. In combination with the endless chain for hod-elevators, the guide-wheels, between which the sides of the chain are made to travel, as described.

7. In combination with the endless chain of a hod-elevator, the flanged wheel and the wheel having a plain surface, for preventing the sagging of the chain, substantially as set forth.

8. In combination with the endless chain or belt of a hod-elevator, the wheels D, having recesses or grooves E' and flanges D', substantially as set forth.

9. In combination with the endless chain or belt of a hod-elevator, the wheels D, provided on their outer side with the safety guiding-flanges D', substantially as and for the purposes described.

In testimony whereof I affix my signature in presence of two witnesses.

ALBERT T. HULL.
